ERNEST GREEN, OF HENDON, LONDON, ENGLAND, ASSIGNOR TO RADIO CORPORATION OF AMERICA, A CORPORATION OF DELAWARE

AERIAL SYSTEM AND FEEDING SYSTEM THEREFOR

Application filed March 24, 1927, Serial No. 177,979, and in Great Britain April 30, 1926.

This invention relates to aerial systems, and feeding systems therefor, and more particularly to aerial systems for use in directional radio telegraphy and telephony.

5 In general, aerial systems for use in directional radio telegraphy and telephony have dimensions of the order of several wave lengths, and are fed with high frequency at a number of points throughout their extent by means of cables.

The object of the present invention is to provide a feeding system for use with such an aerial system in which reflection along the cables shall be reduced to a minimum.

15 In the simplest type of aerial system, comprising a single aerial fed through an aerial transformer and length of uniform cable from a source of high frequency energy, reflections are substantially eliminated when the tune 20 of the aerial and the coupling of the transformer are so adjusted that the effective load at the aerial end of the cable is a resistance numerically equal to the square root of the quotient obtained by dividing the effective 25 inductance by the effective capacity. Hereafter the said resistance, which is, of course, equal to the surge impedance, will be designated by the symbol Ro .

With a more extended aerial system, however, the minimizing or elimination of reflections becomes more difficult. For example, consider a known case of an aerial system comprising four aerials, each fed through an aerial transformer, the primaries of the said 35 aerial transformers being connected together in pairs by two lengths of twin "aerial" cables which are connected together at their mid-points by a length of "intermediate" twin cable which in turn is fed at its mid-point 40 by a "transmitter" twin cable, leading to the source of high frequency energy. If, in such an installation, the aerial loads be adjusted as set out above, reflections will still be set up at the points of juncture, giving rise to 45 strong stationary waves in the cables.

The present invention provides a method whereby such stationary waves may be substantially eliminated in the "transmitter" cable, and reduced in the "intermediate" and 50 "aerial" cables.

In a cable in which the terminal load is not a resistance equal to the surge impedance Ro , stationary waves are set up, but at points in the cable one quarter wave length apart, voltage and current are in phase, that is to say, at those points the effect of the load and cable to such a point is that of a pure resistance. Neglecting attenuation, if at any such point the value of this resistance is $K Ro$, 55 then at the next such point it will be $\frac{1}{K} Ro$, 60 at the next $K Ro$, and so on. For example, in the extended aerial system already referred to, if the aerial loads are adjusted so that there are no reflections in the aerial 65 cables, the load on the intermediate cables at their junctions with the aerial cables will be $\frac{1}{2} Ro$; hence, stationary waves will be set up in the intermediate cables.

According to this invention those cables 70 which connect points of juncture and in which there is liability for stationary waves to be set up (in the manner hereinbefore described), are made an odd number of quarter wave lengths long, so that the effective impedance of each such cable at their own point of juncture is substantially a resistance equal 75 to the number of such cables times Ro .

In this way the impedance of those cables which connect points of juncture, being in 80 parallel at their own point of juncture, will give rise to an effective load equal to that of a resistance Ro , on the next cable towards the transmitter at the point of juncture therewith.

It will be seen that if there be an even 85 number of junctions between the transmitter and any aerial of an aerial system, an arrangement as above described will eliminate stationary waves between the transmitter and the nearest junction. If, however, there be an odd number of junctions, it will be necessary either to provide a transformer at the 90 said junction or adjust the aerial loads (to $\frac{1}{2} Ro$ in the system described) and lengths 95 of aerial cables to give the required effective impedance values ($2Ro$ in the case of the extended aerial system described) at the points of junctions.

The invention is illustrated in the accom- 100

panying diagrammatic drawing, which shows a feeder system adapted to supply energy to an aerial system comprising four aerials.

5 Referring to the drawing, A1, A2, A3 and A4 are aerials fed through cable sections 1, 2, 3, 4, 5, 6, 7, by way of junctions T1, T2 and T3. It will be seen that if the aerial loads are correctly adjusted so that
10 there will be no stationary waves in the sections 1, 2, 3, 4, the two sections 1 and 2, in parallel at the junction T1, constitute a load $\frac{1}{2} R_o$ upon the section 5. Similarly the sections 3, 4, in parallel constitute a load $\frac{1}{2} R_o$ upon the section 6. It follows, therefore, that stationary waves will be set up in the sections 5 and 6. In accordance with the present invention, the sections 5 and 6 are made each an odd number of quarter wave lengths long, so that the effective impedance of each at their junction T3 is substantially that of a pure resistance $2R_o$. The two loads $2R_o$, in parallel upon the section 7, constitute a terminal resistance R_o thereon and consequently no stationary waves will be set up therein.

15 The invention may be applied in like manner to a feeder system of any number of junctions, and having any number of branches at the junctions.

20 Again, if desired, the invention may be applied to any convenient part or parts of a feeder system, other junctions being dealt with by definite transforming devices at the
25 said junctions.

The invention is equally applicable to the reception as to the transmission of wireless telegraphy and telephony.

30 Having thus described my invention, what
35 I claim is:

40 1. A feeder or the like for feeding high frequency energy to a plurality of antennæ comprising a transmitter twin cable, an intermediate twin cable, and a pair of twin aerial cables coupled at their ends to said antennæ through a coupling which impresses a load on said aerial cables equal to their surge impedance whereby standing waves are eliminated in said twin aerial cables, said intermediate twin cables being connected at its ends to the mid-points of each of said twin aerial cables and at its mid-point to said transmitter twin cable and being an odd number of quarter wave lengths long in each
50 branch whereby standing waves are eliminated in said transmitter twin cable.

55 2. An energy transfer system between a high frequency source and a plurality of high frequency circuits comprising a path from said source, a pair of paths connected to the first mentioned path, said pair of paths each having a length equal to an odd number of quarter wave lengths of the energy being transferred, and means electrically connecting said pair of paths to said plurality of

high frequency circuits, said means impressing a load on said pair of paths which is equal to one-half the surge impedance of said paths.

3. An energy transfer system between a high frequency source and a plurality of high frequency circuits comprising a path from said source, a pair of paths connected to the end of said path, each of said plurality of paths having an effective length equal to a quarter wave length of the energy being transferred, and means electrically connecting said plurality of paths to said high frequency circuits, said means impressing loads on the ends of said plurality of paths of such values that their reciprocals will combine at the end of the first mentioned path to form an impedance equal to the surge impedance of said first mentioned path.
